UNITED STATES PATENT OFFICE

153,862

DESIGN FOR A COMBINED PORTABLE MOTION-PICTURE PROJECTING MACHINE AND CARRYING CASE THEREFOR

William Charles De Vry, Chicago, Ill., assignor to
De Vry Corporation, Chicago, Ill., a corporation
of Illinois

Application November 19, 1947, Serial No. 142,649

Term of patent 3½ years

(Cl. D61—1)

To all whom it may concern:

Be it known that I, William C. De Vry, a citizen of the United States and a resident of Chicago, in the county of Cook and State of Illinois, have invented a new, original, and ornamental Design for a Combined Portable Motion-Picture Projecting Machine and Carrying Case Therefor, of which the following is a specification, reference being had to the accompanying drawings, forming a part thereof, and in which:

Fig. 1 is a perspective view of a combined portable motion picture projecting machine and carrying case therefor, in closed condition, showing my new design the opposite side and end being plain; and

Fig. 2 is a side elevational view of the same, with the parts in open condition.

I claim:

The ornamental design for a combined portable motion-picture projecting machine and carrying case therefor, as shown and described.

WILLIAM CHARLES DE VRY.
